SELF-PROPELLED LOADER

Louis J. Keller, Milnor, N. Dak.

Filed Apr. 6, 1960, Ser. No. 60,072

Term of patent 14 years

(Cl. D14—3)

Fig 1

Fig 2

FIG. 5

FIG. 6

FIG. 1 is a top plan view of a self-propelled loader showing my new design;

FIG. 2 is a perspective view taken from the right front side;

FIG. 3 is a perspective view taken from the left rear side;

FIG. 4 is a right side perspective view;

FIG. 5 is a front elevational view; and

FIG. 6 is a rear elevational view.

The dominant features of my design reside in the portions shown in full lines.

The portions shown in broken lines in FIG. 1 are broken away for convenience of illustration.

I claim:

The ornamental design for a self-propelled loader, as shown and described.
